LAUNDRY CART

Lena Bishop and Orra Bishop, San Diego, Calif.

Application September 8, 1936, Serial No. 99,762

2 Claims. (Cl. 280—51)

Our invention relates to a laundry cart, particularly adapted for holding and conveying the laundry after it is washed to the clothes line for drying or for any similar purpose, and the objects of our invention are:

First, to provide a laundry cart of this class in which the clothes receptacle always remains in an upright position regardless of the slant or contour of the ground upon which it is operated; 10
Second, to provide a laundry cart of this class which automatically locks against movement when it is stopped and released;

Third, to provide a laundry cart of this class in which the clothes are supported in a receptacle 15 in a position so that one does not need to stoop to reach the clothes when hanging them on a line;

Fourth, to provide a laundry cart of this class with a clothes pin receptacle readily removably supported at one side of the clothes receptacle so that the pins are readily accessible while hanging the clothes;

Fifth, to provide a laundry cart of this class which automatically keeps the clothes and clothes pin receptacle in upright position and automatically locks the cart when it is stopped and let go without any attention of the operator;

Sixth, to provide a means for adjusting the locking apparatus; and

Seventh, to provide a laundry cart of this class which is very simple and economical of construction, efficient, easy to operate, and which will not readily deteriorate or get out of order.

With these and other objects in view as will appear hereinafter, our invention consists of certain novel features of construction, combination, and arrangement of parts and portions as will be hereinafter described in detail and particularly set forth in the appended claims, reference being had to the accompanying drawings and to the characters of reference thereon which form a part of this application in which:

Figure 1 is a partial elevational and sectional view from the line 1—1 of Fig. 6; Fig. 2 is an enlarged fragmentary elevational view of the ratchet arc and ratchet connection therewith; Fig. 3 is a transverse sectional view thereof from the line 3—3 of Fig. 2; Fig. 4 is a fragmentary side elevational view of the clothes receptacle and its support shown at right angles to that of Fig. 1 of the drawings; Fig. 5 is a sectional view on an enlarged scale from the line 5—5 of Fig. 4; Fig. 6 is a front elevational view of our laundry cart; Fig. 7 is a top view thereof from the line 7—7 of Fig. 6; Fig. 8 is an enlarged sectional view from

the line 8—8 of Fig. 7 and Fig. 9 is a sectional view from the line 9—9 of Fig. 6.

Similar characters of reference refer to similar parts and portions throughout the several views of the drawings:

The clothes receptacle 1, clothes receptacle supporting bars 2 and 3, clothes receptacle central support 4, clothes pin receptacle 5, handle 6, ratchet arc 7, ratchet lever 8, axle 9, and wheels 10 and 11 constitute the principal parts and portions of our laundry cart.

The clothes receptacle 1 is a pail-like receptacle with tapered sides, preferably tight, and adapted to hold the wet clothes ready for hanging on the line or other similar disposal. It is provided with an upper reinforcing band 1a on its upper side and with four side reinforcing bands 1b, 1c, 1d, and 1e shown best in Fig. 9 of the drawings, which reinforcing bands extend across the bottom to the middle, also shown best in Fig. 9 of the drawings. Secured to this middle portion is a central support 4 which extends downwardly from the center of the bottom of the receptacle 1 and is provided at its lower end with a longitudinal slot 4a which is adapted to receive a bolt 4b shown best in Fig. 5 of the drawings, with a washer 4c on one side of the member 5 and the other side of the member 4 is the ratchet arc 7, on the opposite side of which is a spring connecting hook 4d to which is connected a spring 4e which extends upwardly and connects with the bottom of the receptacle 1 by means of a hook 4f all shown in Figs. 4 and 5 of the drawings. Thus the ratchet arc 7 is suspended relatively to the receptacle 1 by means of the spring 4e and shiftable by means of the slot 4a in the member 4.

Pivottally connected at opposite sides of the member 1 are the clothes receptacle supporting bars 2 and 3 which extend downwardly and are looped around the axle 9, which axle 9 is square, thus providing means for holding the axle 9 in certain torque relation with the receptacle 1 by supporting the receptacle 1 at the upper end of the supports 2 and 3 so that it assumes an upright position at all times. Supported near the lower ends of the supports 2 and 3 is the handle member 6 which extends backwardly at 6a and upwardly at 6b and then forms a cross bar 6 as a handle, which is preferably round in cross section as shown.

Secured to the axle 9 at its middle is a ratchet lever 8 which is in certain rigid torque relation with the axle 9 and secured in this manner by means of a cap member 8c as shown best in Fig. 1 of the drawings. The opposite ends of the lever

8 are provided with ratchet members 8a shown best in Fig. 2 of the drawings which are adapted to engage teeth 7a on the upper side of the opposite ends of the ratchet arc 7. This lever 8 is also 5 provided with rollers 8b adjacent the ratchet members 8a which are adapted to engage the lower surface of the member 7 when the member 7 is in such position that the ratchet engaging portion of the members 8a are out of engagement 10 with the teeth 7a, there being sufficient space between the rollers 8b and the lower side of the ratchet arc 7 to permit enough shift to release the ratchet from the ratchet teeth. The one end of the member 7 is provided with a flat base portion 7b which is provided with extended prongs 7c which are adapted to enter the ground to form a lock for the cart when the member 7b is resting on the ground. The opposite end of the member 7 from the flat member 7b is provided with a 15 bifurcated portion 7d in which is revolubly mounted a wheel member 7e so that by shifting the receptacle 1 over the center of the wheel, the wheel member 7e may rest upon the ground and the member 7b elevated so that the wheel 7e may 20 be used where the ground is relatively flat and a lock is not necessary.

The receptacle 1 is provided on one side near its upper edge with a socket member 5a which is adapted to receive the end of a bracket 5b which 25 is secured to a clothes pin receptacle 5 all as shown best in Fig. 8 of the drawings, which clothes pin receptacle is open at its upper side adapted to receive and hold the clothes pins, and the receptacle may be removed by raising the 30 bracket member 5b out of the socket member 5a and may be similarly inserted.

The operation of our laundry cart is as follows: If it is desired to use the lock member shown by the base 7b, the ratchet members 8a are positioned 40 in connection with the ratchet arc teeth 7a near the one end of said teeth as shown best in Fig. 1 of the drawings, and with the base 7b on the ground or floor, the wet clothes are placed 45 in the receptacle 1, then the operator takes hold of the handle 6, raises the base member 7b slightly off of the ground and runs the cart to the place where it is desired to hang the clothes; then

by lowering the member 7b onto the ground, the cart is locked against movement either forwardly or backwardly, and the receptacle 1 always maintains an upright position high enough so that the operator does not have to stoop in taking the 5 clothes from the receptacle and placing them on the line, and it will be noted that regardless of the amount of tilting or slant of the ground the receptacle always maintains an upright position and the cart is locked against movement. 10

Though we have shown and described a particular construction, combination, and arrangement of parts and portions, we do not wish to be limited to this particular construction, combination, and arrangement, but desire to include in 15 the scope of our invention, the construction, combination, and arrangement substantially as set forth in the appended claims.

Having thus described our invention, what we 20 claim as new and desire to secure by Letters Patent is:

1. In a laundry cart, a pair of wheels in spaced relation, an axle connecting said wheels, supports extending upwardly and connected with said axle, a receptacle pivotally supported at the upper 25 ends of said supports, a ratchet lever secured to said axle and extending forwardly and backwardly thereof provided with ratchets at its opposite ends, and a ratchet arc pivotally and shiftably supported on said receptacle and engageable by 30 the ratchets on said ratchet lever.

2. In a laundry cart, a pair of wheels in spaced relation, an axle connecting said wheels, supports extending upwardly and connected with said axle, a receptacle pivotally supported at the upper ends 35 of said supports, a handle member in connection with said supports intermediate their ends and extending backwardly past the periphery of said wheels, a ratchet lever secured to said axle and extending forwardly and backwardly thereof provided with ratchets at its opposite ends, and a ratchet arc pivotally and shiftably supported on 40 said receptacle and engageable by the ratchets on said ratchet lever.
